MULTI-CELL BULK CONTAINER

BACKGROUND OF THE INVENTION

1. Field of the Invention

The invention is in the field of containers formed of corrugated board and having multiple cells or compartments.

2. Description of the Prior Art

Various types of multicell containers are used for shipping bulk, flowable materials such as synthetic resins, crude reproject synthetic rubber, liquid vinyls, frozen foods, etc. These materials have substantial weight per unit volume and the conventional large multicell containers (some of the order of 3 to 6 feet in height) utilized have various means for reinforcing the panels of the outer cells to prevent bulging, one such means used widely being metal banding about the body of the container. Normally, these banded containers have one or more corner joints or seams and, with the band reinforcing against bulging of the wall panels, these taped or stitched corner seams tend to bulge and tear. This exposes the contents of the container to contamination by dust and dirt and, particularly in the case of synthetic rubber, such chance contamination of the material is highly undesirable. The interior surfaces of the container cells are, for many applications, coated with a release coating to prevent the bulk product from adhering to the cell walls. This release coating, of course, also prevents adherence of glue or other adhesive so that any gluing of the cells into assembled relation must fasten cell surfaces which do not, in assembly, become interior surfaces, that is, surfaces engaging the container contents. The loading of the containers, and hence the bulging stress, can be quite severe since the containers may be, as an extreme, 8 feet in height and holding 3000 pounds of a bulk, flowable product. Stacking of the containers in warehouses or in shipping aggravated the problem by increasing the loading on the lower tiers of containers.

SUMMARY OF THE INVENTION

The present invention is embodied in a multicell container having reinforced outer end walls, the container having its cell components and reinforcing panels glued together can then be folded into a relatively flat or collapsed contour, making unnecessary the gluing together of the individual cells at the point of use. The primarily important feature of the structure is that it has no external seams or joints and the joints inherent in the formation of the individual cells are staggered, or transversely spaced, with relation to each other so that no lines of weakness or stress concentration are developed in the container even under extreme loading.

BRIEF DESCRIPTION OF THE DRAWINGS

FIG. 1 is a perspective view of a container assembly embodying the present invention.

FIG. 2 is a perspective view showing the container assembly at an intermediate stage in its assembly.

FIG. 3 is a top plan view of a reinforcing panel for the container at an intermediate stage in its assembly with portions broken away to indicate the direction of extension of the corrugations.

FIG. 4 is an end view of the reinforcing panel after complete assembly.

FIG. 5 is a side view of the container assembly without the bottom tray, with the container being shown in partially collapsed or folded condition ready for transport or storage.

FIG. 6 is a top plan view of the blank from which the bottom tray is formed in showing reinforcing tape or band in place.

FIG. 7 is a perspective view of the tray formed from the blank shown in FIG. 6.

DESCRIPTION OF THE PREFERRED EMBODIMENT

Referring initially to FIGS. 1 and 2, the multicell container of the present invention is illustrated as including three cells indicated generally at 10, 11 and 12. As may be seen in FIG. 2,

the cells may be provided with conventional end closure flaps 13 and might also incorporate conventional top closure flaps for closing the upper end of the cells, however, top closure flaps have been omitted in the embodiment shown. Reinforcing side panels or pads 14 overlie the outer side panels 12c and 10c. Enclosing the lower portion of the cells and the pads 14 is a bottom tray 16.

The cells are each formed from a sheet of corrugated board which has been scored to permit folding into a rectangular configuration as shown in FIG. 2. In conventionally formed containers the manufacturers joint, or line of juncture closing the box into a tubular configuration is normally at one corner of the box. However, in forming the cells of the present container assembly, the line of juncture occurs intermediately in one of the side panels. The line of juncture for the cell 12 is identified at 17 in FIG. 2, that for the cell 11 is identified at 18 and the joint or line of juncture for the cell 10 is illustrated at 19.

The cells are held in side-by-side relation by adhering, by means of glue or other fastening means, the junctional side panels to the adjacent cell side panels. In FIG. 2 the adhering substance is indicated at 21 and the junctional panel 12a of the cell 12 is adhered to the side panel 11a of the cell 11. The junctional side panel 11a of the cell 11 is adhered to the junctional side panel 10a. Where two junctional panels are secured together, the line of junctures, such as junctures 18 and 19 are spaced or staggered with relation to each other thus avoiding weakening the wall structure formed by the panels.

The preferred construction of the reinforcing end panels 14 is illustrated in FIGS. 3 and 4. The panels or pads 14 are each formed by a sheet of corrugated board 21 having corrugations extending vertically as indicated at 21a in FIG. 3 with the sheet being scored as indicated at 22 and 23. Overlying the central portion of the sheet 21 is an additional sheet 24 of corrugated board having its corrugations extending transversely to those of the sheet 21, as indicated at 24a. The sheet 24 is glued to the adjacent surface of the sheet 21 and the portions of the sheet 21 outwardly of the score lines 22 and 23 are folded over the sheet 24 as indicated in FIG. 4 and are glued or otherwise secured to the surface of the sheet 24.

FIG. 5 illustrates the container of FIG. 1 without the bottom tray 16 and in collapsed condition as it would be when stored or during shipment to the user of the container. As will be evident from FIG. 5, the inner surfaces of the end pads 14 are glued or otherwise secured to the adjacent cell panels 12c and 10c, the glued surfaces being indicated at 31. In FIG. 5, the glued surfaces of the FIGS. are indicated at 32.

Referring to FIGS. 6 and 7, the tray structure 16 will be described in detail. The tray is formed of a sheet of corrugated board which is scored to provide a primary panel 41 having marginal flaps 42, 43, 44 and 46 extending from its side surfaces. Two opposite flaps 42 and 44 also have extending from their ends the tabs 47 and 48 extending the length of the flaps 42 and 44 and, additionally, extending across the pads 47 and 48 are strips of reinforcing tape 49 and 51, the tape being preferably formed of a high tensile strength material such as fiberglass. As may best be seen in FIG. 7, when the tray is erected the tabs 47 and 48 are secured by gluing or stapling or other suitable fastening means to the adjacent surface of the flaps 43 and 46 and when so arranged, the tape strips 49 and 51 extend around the corners of the tray and serve to reinforce the tray corners.

When completed and erected the container may utilize both a top and bottom tray, the top tray acting as a closure or, as previously mentioned, the top of the container may be provided with conventional closure flaps. The completed FIGS. has no corner joints and the staggered line of junctures of the panels forming each cell provide unweakened interior partitions between the cells.

We claim:

1. A multi-cell container assembly for bulk material of substantial mass comprising a plurality of cells each formed from a sheet of corrugated board folded into a tubular configura-

tion which is rectangular in cross section, said cells being fastened to each other in side-by-side relation by adhering to each other the contiguous side panels of adjacent cells, a rectangular bottom tray enclosing the base of the cells and having sidewalls extending upwardly to shield the lower portion of the cell side panels, reinforcing panels overlying the exposed side panels of the outermost cell at each end of the con-

tainer assembly and extending between the adjacent tray sidewalls and the side panels of said outermost cells, each of said reinforcing panels being formed of a first sheet of corrugated board folded upon itself so as to enclose a second sheet of corrugated board the corrugations of one sheet extending transverse to the corrugations of the other sheet.
